UNITED STATES PATENT OFFICE

156,454

COMBINED WRITING DESK AND CHAIR

Stephen Nemes, Chicago, Ill.

Application September 21, 1948, Serial No. 148,677

Term of patent 14 years

(Cl. D15—1)

To all whom it may concern:

Be it known that I, Stephen Nemes, a citizen of the United States, residing at Chicago, in the county of Cook and State of Illinois, have invented a new, original, and ornamental Design for a Combined Writing Desk and Chair, of which the following is a specification, reference being made to the accompanying drawing, forming a part thereof.

In the drawing:

Fig. 1 is a perspective view of a combined writing desk and chair embodying my new design;

Fig. 2 is a top plan view thereof;

Fig. 3 is a side elevational view as seen from the right hand side in Fig. 1; and

Fig. 4 is an end elevational view as seen from the right hand end in Fig. 3.

I claim:

The ornamental design for a combined writing desk and chair, substantially as shown.

STEPHEN NEMES.
